UNITED STATES PATENT OFFICE.

CHESTER B. MILLS, OF BROOKLYN, NEW YORK, ASSIGNOR TO THE SPERRY GYROSCOPE COMPANY, OF BROOKLYN, NEW YORK, A CORPORATION OF NEW YORK.

AUTOMATIC STEERING FOR DIRIGIBLE CRAFT.

Application filed June 19, 1922. Serial No. 569,295.

This invention relates to the navigation of all kinds of craft, more especially to the steering of dirigible craft such as vessels, and aircraft which are guided by means of a rudder. In the automatic steering of dirigible craft, especially where the rudder and the driving power are both located at the stern of the craft, as in ships, there is a tendency to throw the craft into unstable equilibrium so far as direction is concerned. This is indicated by the constant tendency of such craft to deviate from the true course, an act known as yawing. It is one object of this invention to reduce or substantially eliminate this tendency to a degree which may be known as anticipation. One form of apparatus for accomplishing this function is disclosed in the patent to Elmer A. Sperry, No. 1,360,694 dated November 30, 1920, on which this invention is an improvement. After protracted investigation, including sea trials which have been followed to the extent of finally successfully steering very large ships, means have been developed, as herein disclosed to accomplish these functions which are simple, inexpensive and operate with less lag.

One of the objects of the invention and an improvement effected by it is the preventing of the ship when swinging back to her course from swinging beyond the proper heading. In maritime parlance, this is termed "meeting" the ship. To accomplish this automatically, means are provided to retard the angular movement of the ship, especially as it approaches such heading. By this means the yaw is damped out effectively.

It is a further object of this invention to provide means whereby a new course may be set and means for automatically directing the vessel rapidly into said course.

A further object is the provision of means for automatically setting the rudder, when it is desired to swing the vessel through a desired angular distance, to a degree proportional to said angular distance.

A further object is the provision of an automatic steering device which may be controlled from a master gyroscopic compass, but so constructed as to prevent transmission of the "hunt" of said compass to the steering device.

A further object is the provision of an

alarm or signal to give a suitable indication or warning of unusual and dangerous movements of a vessel.

Other objects and advantages will in part be obvious and in part specifically pointed out in the specification.

In the accompanying drawings,

Fig. 1 is a front elevation of that portion of the steering apparatus which is adapted to be placed in the pilot house of a vessel, and showing a preferred form of my invention applied thereto.

Fig. 2 is a vertical section through the master controller shown in Fig. 1.

Fig. 2^A is a detail of a portion of the mechanism for preventing transmission of the "hunt" of the compass.

Fig. 3 is a front elevation similar to Fig. 1 but employing another form of master controller.

Fig. 4 is a plan view of the controller shown in Fig. 3.

Fig. 5 is a vertical section of the master controller shown in Fig. 3.

Fig. 6 is a plan view of the controller shown in Figs. 1 and 2.

Fig. 7 is a plan view of the auxiliary control device which operates in conjunction with the master controller and may form a part thereof.

Fig. 8 is a front elevation of the device shown in Fig. 7.

Fig. 9 is a vertical section through the relay portion of the device shown in Fig. 7.

Fig. 10 is a wiring diagram of one form of course control device.

Fig. 11 is a wiring diagram of a second form of course control device.

Fig. 12 is an original record of a ship's course, showing the results of automatic steering on the course of a vessel.

Referring to Figs. 1 and 2 of the drawings, for governing the course of a ship, I locate, preferably in the pilot house of the ship, a master controller 1 from which the rudder is automatically controlled. Said controller may assume a variety of forms. In Fig. 1 it is shown as mounted on a bracket 2 secured to the stand 3 supporting the standard steering repeater compass 4. Adjacent said stand are shown the pilot wheel 280 which it will be understood controls the steering engines in the usual manner, and the magnetic compass

housing 6. In Fig. 3 a different form of master controller 1' is shown mounted on a stand 3' and which performs both the function of a steering repeater compass and a master controller. Referring first to the form shown in Figs. 1 and 2, there is provided a casing 10 having a transparent cover 11 held in position by a bezel 12, said casing having mounted therein a repeater motor 13 controlled from any form of azimuth indicator, preferably from a gyroscopic compass (not shown). Said motor is connected to a member 15 which may carry a pointer 16 or other course indicator, cooperating with a scale 17 on a settable annulus 55. The compass will thus maintain pointer 16 fixed relatively to the scale, if the gearing employed between motor 13 and the pointer is of the same ratio as that between the master compass and its transmitter. In practice, however, I prefer to employ less reduction gearing between the repeater motor 13 and the member 15 so that any deviation of the ship from its course is magnified. As shown, the shaft 20 of the motor 13 is provided with a pinion 21 meshing with a gear 22 which drives, in turn, pinion 35. Said pinion 35 meshes with gear 36 which is shown as carrying member 15. To prevent the "hunting" action of the gyro compass from affecting member 15, I prefer to provide a lost motion connection between gears 22 and 35. Gear 22 is secured to a bushing 23 journaled in a boss 30 carried by an arm 31 fixed to the motor frame. A shaft 24 extends through said bushing and carries a cross-bar 25 at its upper end extending between prongs 26 on the upper end of bushing 23 and between the wedge shaped slots 27 formed in a member 28 also journaled in boss 30 and having a gear 35 fixed thereto and meshing with a gear 36 to which member 15 is secured. It will thus be apparent that the "hunt" is transmitted by shaft 20 and gears 21 and 22, bushing 23 and its prongs 26 to the cross piece 25 enclosed between said prongs. The cross piece, however, has considerable lost motion in the wedge shaped slots 27 before it engages member 28 to rotate gears 35 and 36, and member 15. This lost motion is sufficient to take up the "hunt" and prevent its transmission to the member 15.

By moving cross-piece 25 upwardly toward the apex of the wedge-shaped slot, it is apparent that there will be less free motion before said cross piece engages member 28, while by moving said cross piece downwardly toward the divergent end of the slot, the lost motion will be increased. The amount of lost motion may be regulated by providing for vertical adjustment of the cross piece and the shaft 24 to which it is fixed. For this purpose, there is provided a vertically movable cam member 37 having a cam face 38 with which engages an adjusting screw 39 threaded through casing 10 and operable

from outside thereof by a nut 40 fixed to a shaft 41 carrying a forked member 42 between the prongs of which engages a pin 43 fixed to the screw 39. By rotating nut 40 to rotate screw 39 inwardly or outwardly, cam member 37 is raised or lowered to raise or lower shaft 24 and cross piece 25. A spring 44 tends to return the shaft 24 and cross piece 25 to lowered position.

Although the oscillatory movements of the "hunt" are not transmitted to the member 15, any deviation of the ship from its course will cause relative displacement of pointer 16 and scale 17. At the same time there is brought into action mechanism which operates the rudder in such a manner as to bring the ship back to its original course. One form of mechanism is as follows: In addition to pointer 16 there is fixed upon member 15 a circuit closing device comprising a pair of trolleys 50 contacting with split contact rings 51, 52, 53 (see Fig. 10) separated from each other by insulation 54. Said contact rings are carried by a rotatable ring 55 having a rack 56 fixed thereto so that it may be rotated from outside the casing by a handle 60 operating a pinion 61 which meshes with said rack. The ring is set to cause the ship to head in any desired direction by reference to the repeater compass 4 (Fig. 1). When the ship is on its course, contacts 50 normally engage the insulation 54, but as soon as the ship deviates, a relative movement of trolley 50 and ring 55 occurs so that contacts 50 engage contact 51 or 52, depending upon the direction of deviation, to energize field coil 62 or oppositely wound field coil 63, respectively, of a steering engine controlling motor 65, to drive rudder 66 in the direction which will tend to bring the ship back to its course. Said motor may either drive the rudder directly or through the ship's telemotor and steering engine system (hereinafter described) and may be located either forward adjacent the pilot wheel and controller or aft adjacent the rudder.

Referring to Fig. 1, it will be observed that the repeater compass 4 is contained in a separate casing from casing 10 containing the master controller which in this instance is provided with an arbitrary scale 17. The steering compass and master controller may, if desired, be mounted in the same casing, as shown in Figs. 3 to 5, in which case the standard repeater card 252 cooperates with the settable course indicator 250. For this purpose pointer 250 is mounted upon a shaft 251 concentric with compass card 252 controlled from a repeater motor 13'. The entire mechanism is enclosed in a casing 255 having the usual glass cover 256 and bezel 257. The compass card is rotated by the compass repeater motor 13' through gears 258, 259 to rotate shaft 260 and gear 261 thereon, gear 261 meshing with gear 262 on a bushing 263 jour-

naled in a partition plate 264, said compass card being fixed to the upper end of said bushing.

To set the pointer relative to the compass card, the usual handle 60 may be provided which operates by means of bevel gear 61, a differential comprising upper gear 265 and lower gears 266, 267, the gears 265 and 267 meshing with gears 270 and 271 of a planetary member 269 fixed to shaft 260. Since shaft 260 is rotated by the repeater motor, operation of handle 60 will rotate gears 270 and 271 about their axes to rotate gear 265 and gear 273 fixed thereto, said gear 273 meshing with gear 274 fixed to the pointer shaft 251. Fixed to gear 265 is a trolley 50 meshing with contact strip 51 arranged in the form of rings, as in the Fig. 2 device hereinbefore described, except that said rings are here shown positioned to one side of the casing. It will be obvious that when a new course is set by handle 60, trolley 50 will be moved along the contact strip, and that when the ship turns to move the contact strips relative to the trolley, the same circuits will be established, as have been described hereinbefore to move the ship to a new course or to bring it back after it has moved off its course.

In both the modifications shown in Fig. 1 and Fig. 3, the rudder may be operated either from the motor 65 as described through shaft 65', or by the usual steering wheel 280 operated by hand. The latter may be found desirable at times, as when entering or leaving port. For this purpose, a clutch 281 may be provided for throwing in or out the motor drive which may operate through a link 65' connecting the motor and the rudder operating means. It will of course be understood that both the pilot wheel 280 and motor 65 may operate the rudder through any desired form of steering engine on steamers of sufficient size to employ steering engines.

It should also be noted that in the form of master control shown in Fig. 3 and in the auxiliary control device 70 as illustrated in Figs. 7 to 9, the contacts are rotated through a greater angle than the angle through which the compass apparently turns, thus in referring to Fig. 5, it may be assumed that the repeater card 252 is rotated through the same angle that the compass rotates through. This being the case, it will be readily apparent that the trolleys 50 are rotated through a much greater angle, since they rotate directly with the gear 265 and pinion 273, while the compass card only rotates through, say one-tenth of that angle, due to the relative size of the pinion 273 and the gear 274. Also in Figs. 7 and 9, the contractor is shown as rotated from the repeater motor, with only a one step reduction. Since it is common practice in the Sperry gyroscopic compass for the repeater motor to rotate one hundred and eighty times for one revolution of the com-

pass, it will be readily seen that the commutator may be turned through a much larger angle than the compass. In fact, I prefer to turn the commutator through a larger angle than the trolleys 50, so as to make it more quickly responsive to slight changes in the heading of the ship, for the purposes which will readily be apparent from the foregoing description of the auxiliary control device as hereinafter set forth.

If the problem of automatic steering were solved by the mere provision of settable, compass governed contacts, the solution would be simple, but as above explained, a ship does not stay on a course for any great length of time, but practically continually tends to yaw off its course, swinging first to one side and then the other of the proper heading. As a means of reducing yawing, I have devised a means which, after throwing the rudder outwardly to counteract the yawing movement, starts the rudder back before the ship has regained its course, and in many cases brings the rudder to a point beyond its central position before the ship regains its course. The yaw to the opposite side of the course is thus anticipated and prevented, for otherwise, the ship would be carried beyond its true course in the other direction. For this purpose there is interposed in the circuit between contacts 50, 51, 52 and the oppositely wound coils of the rudder control motor 65, or otherwise introduced the auxiliary control device 70 (see Figs. 7, 8 and 9), which is responsive to angular movement of the ship, whether that movement be toward or away from its proper course.

Said device 70 may be incorporated in the master controller itself, but I prefer to separately mount it, say, on a panel. It is mechanically operated from a repeater motor 69 similar to motor 13 and also operated from the master compass. The device comprises a set of brushes 71 and 72 normally in engagement with insulated contact sectors 73 of a commutator 75 connected to repeater motor 69, so as to be operated thereby only by changes in the direction of rotation thereof. When the ship changes its course, therefore, the commutator is operated from the repeater motor, so that brush 71 will engage a contact 76, or brush 72 will engage a contact 77, depending upon the direction of the yawing movement or change in course, so that a circuit will be established from trolley 50 through contact 51, lead 79, contact 76, brush 71, lead 80, to energize coil 81 to close the normally open relay 82, closing a circuit through lead 83, normally closed relay 84, to coil 63 of the motor 65; or from trolley 50, contact 52, lead 87, contact 77, brush 72, lead 88 to energize coil 89 to close a normally open relay 90, closing a circuit through lead 91, normally closed relay 92, to coil 62 of the motor 65, to drive the motor in

the corresponding direction and so drive the rudder 66.

If either of the above circuits is closed to operate the motor to drive the rudder in a given direction for counteracting yawing of the ship, as soon as the ship begins to turn under the influence of the rudder, i. e., turn in a direction opposite to the yawing movement, means are provided by this invention for reversing the direction of rotation of the rudder-controlling motor and hence, returning the rudder to or near its initial position. Thereafter, the momentum of the ship will carry it back to its course, whereas, if the rudder were not returned at the specified time, the momentum of the ship would carry it beyond its true course.

For the purpose of illustrating the operation of the device, assume that the ship has yawed so that trolley 50 has moved 5° along contact 51. As the ship turns clockwise, the commutator 75 turns counterclockwise relatively thereto, because of its connection to the repeater motor 69, so that commutator 75 would ordinarily tend to travel say 10° with respect to the brushes, but stops 119, 120 on the commutator and fixed frame, respectively, are provided for limiting the relative movement of the commutator with respect to the ship to a small angle, and hence with respect to brushes 71 and 72. So that after a small movement of the commutator relative to the ship, the stops 119, 120 engage and the commutator is thereafter held stationary with respect to the ship, any further movement of the commutator relative to its shaft being taken up by a slip-friction connection shown in Fig. 9. The commutator therefore, is immediately displaced with respect to the brushes upon a change in the angular movements or direction of yaw of the ship, whether that change be toward or away from the proper course.

Referring to said Fig. 9, a shaft 95 is driven from the shaft 96 of the repeater motor through gears 97 and 98. In order to prevent transmission of the "hunt" of the compass to the commutator 75, there is provided a lost-motion connection between the shaft 95 and said commutator, in the form of a projecting finger, or bar 100, having frictional engagement with said shaft by means of friction discs 101 and 102 on shaft 95. Disc 101 is provided with a hub 104 which is pinned to shaft 95 by a pin 106 passing through said hub and through an elongated slot (not shown) in the shaft 95 to permit longitudinal movement of said disc along said shaft. Disc 102 rests upon a shoulder formed on shaft 95, and disc 101 may be moved relative to disc 102 to vary the frictional contact between the disc and bar 100. For this purpose, a spring 107 at one end presses disc 101 towards disc 102 and at the other end engages a nut 108 screw-threaded upon the end

of shaft 95, so that by operating said nut, spring 107 may be compressed to a greater or lesser degree to apply more or less friction between discs 101 and 102, and bar 100. Felt washers 105 are preferably interposed between the bar and the discs. In this manner, the bar 100 is oscillated together with shaft 95 corresponding to the "hunt" movements of the compass. Engagement between the commutator and the bar 100 is effected through pins 109, 110, engaging in openings in the commutator plate 111. Pin 109 is preferably carried by a rotatable arm 99 and is of the spring pressed type, so that it may be withdrawn from any opening 103 and, by rotating arm 99, inserted in any other opening 103 to vary the amount of lost-motion between the pins, to take care of various "hunt" movements. Any deviation in the course will cause movement of shaft 95 beyond the limits of the "hunt" to cause bar 100 to engage pin 109 or 110 to move the commutator in a direction opposite to the turning of the ship. The brush 71 or 72, therefore, slides along contact 76 or 77 depending upon the direction of movement of the commutator. After a short distance, however, stops 119 and 120 engage to prevent further relative rotation of the commutator, and thereafter the commutator remains stationary in the extreme position until the ship starts turning in the other direction. When the stops 119 and 120 engage, the shaft 95 turns to overcome the frictional engagement between discs 101 and 102 and bar 100, so that the latter is held stationary relative to the ship while the shaft continues to rotate. The commutator plate 111 is provided with a hub 112, said hub operating within a hub 113 fixed to the fixed frame and supporting said plate 111.

The brushes are pivoted as at 115 on a fixed plate 116 carried by frame 114, said brushes being held in engagement with the commutator by springs 117. The movement of the commutator being thus narrowly limited, as soon as the ship starts back under the influence of the outwardly positioned rudder, the motor 69 rotates the commutator to carry brush 71 off contact 76 (in the example here discussed) to break the circuit through coil 63 while trolley 50 is still on contact 51. The ship, however, continues to move in the return direction, commutator 75 carrying brush 72 into engagement with contact 77. No circuit is established through the reverse coil 62 to return the rudder, because contact 50 is still in engagement with contact 51 and hence has no connection to brush 72. There are therefore provided additional brushes 129 and 130 normally in engagement with insulating strips 131 on commutator 75. While brush 71 engages contact 76, brush 129 engages contact 132, and by main lead 140, lead 141, contact 132, brush 129, lead 133, and normally closed relay 134, continues along

the same circuit, as that through contact 51 and brush 71 to relays 82 closing a circuit leading through relay 84 to energize coil 63. But as soon as brush 71 leaves contact 76 5 the circuit through relay 82 and hence through coil 63 of the motor is broken, and while trolley 50 is still in engagement with contact 51, further return movement of the ship causes further opposite rotation of the 10 commutator and carries brush 130 into engagement with contact 132. The brushes 129 and 130 are so positioned relative to contact 132 that only one of said brushes can contact therewith at any given time. A circuit 15 is now established from main lead 140 through lead 141, contact 132, brush 130, lead 142, normally closed relay 143, to energize coil 89 to close relay 90. A circuit is then established through relay 92 to the coil 20 62 of the motor to reverse the direction of movement of the rudder. Further return movement of the ship causes the trolley 50 to be carried toward insulation 54, but this return movement is now due solely to the momentum of the ship, the rudder having been 25 returned to substantially central position. By this arrangement the return momentum of the ship is substantially damped out by the time the ship reaches its central position. 30 When the rudder is returned, after the ship has started back, it is held in substantially central position by breaking the circuit established by brush 130 through normally closed relay 143. This is accomplished by 35 establishing a circuit from main lead 140, lead 145 to one end of the rudder, contact 146, lead 152 through coil 147 of relay 143 to open said relay and break the circuit through coil 62 of the motor. The circuit through motor 40 65 is completed by lead 148, rheostats 149, 150 to the other main lead 151, this portion of the circuit being controlled by a relay 200, as will be more fully described hereinafter. If, however, the ship does not reach its 45 proper course, the above cycle will be repeated until it does, as some yawing of the ship is always present to cause actuation of controller 70. If the ship has not sufficient momentum to carry it back to its course it 50 will turn off again. Immediately trolley 50 will engage contact 51 and brush 71 will again engage contact 76 to energize field coil 63 of the motor. This actuates the rudder outwardly as before to give the ship a second 55 return impulse. It will, of course, be appreciated that, the ship having been almost completely returned to its course by the first impulse imparted to it by the rudder, the period of actuation of the rudder before the ship 60 again starts toward its course will be very much less than the first time. The rudder will thus be actuated as often as is necessary to return the ship to its course, each actuation being of smaller duration than the preceding actuation because the deviation of 65 the vessel from its course is diminished at each actuation.

For the purpose of illustration, the circuits have been traced above in connection with the case where the ship yaws clockwise so that trolley 50 engages contact 51, brush 71 engages contact 76, and brush 129 engages contact 132. The circuits established where the ship yaws in the opposite direction will be apparent and the operation is similar. It 70 may be described briefly as follows; trolley 50 engages contact 52, brush 72 engages contact 77, and brush 130 engages contact 132. The circuit lies through trolley 50, contact 52, lead 87, contact 77, brush 72, lead 88, relay coil 89, closing contact 90 and completing a circuit through lead 91, relay 92 to coil 62 of the motor and from main lead 140, lead 141, contact 132, brush 130, lead 142, relays 143 and 90, lead 91, relay 92, also to coil 62. 80 This operates the rudder counter-clockwise to outward position. As soon as the ship starts in the return direction, the brush 72 will move off contact 77 and brush 130 will move off contact 132 to break the circuit through coil 62 of the motor. This is due to the slip friction connection, shown in Fig. 9, which permits only a slight movement of commutator 75 relative to its brushes, while trolley 50 is free to move through the entire angle of deviation, so that brushes 72 and 130 move out of engagement with contacts 77 and 132, while trolley 50 is still in engagement with contact 52. Brush 129 now moves into engagement with contact 132 to establish a circuit from main lead 140, lead 141, contact 132, brush 130, lead 133, relays 134, relay coil 81 closing contact 82 and a circuit through lead 83 and contact 84 to opposite coil 63 of the motor. This returns the rudder, and 90 when the latter reaches a substantially central position, it engages contact 146 to establish a circuit from main lead 140, contact 146, lead 155, to energize coil 156 of relay 134 to open the latter and break the circuit 95 through coil 63 of the motor.

Contacts 157 and 158 are also provided, as limit switches, to cooperate with the rudder in its starboard and port limiting positions, respectively, to control circuits through coils 159 and 160 of relays 92 and 84, respectively, so that as the rudder reaches its limiting positions, the respective relay will be opened to break the circuit through the motor coil 62 or 63. The circuits are as follows; main lead 140, lead 145, contact 157, lead 161, coil 159, to main lead 151; and main lead 140, lead 145, contact 158, lead 162, coil 160 to main lead 151. By energizing coils 159 and 160, the circuit through the coils 62 and 63 respectively, of the motor are broken.

It will be apparent that if the rudder is thrown outwardly rapidly, it is probable that its momentum would carry it to the limits 130

157 and 158, which may be a much greater throw than is necessary to counteract the yaw if the latter is small. It is desirable therefore, to operate the rudder slowly outwardly, 5 (in the case where there are no intermediate limit switches) so that the latter may be moved through any desired small angular distance. For this purpose, when the circuit through the motor is closed, the current 10 passes through coil 201 of relay 200 to open the latter and cause the current to pass from main lead 151 through both resistance coils 149 and 150 to operate the motor, and hence, the rudder, slowly. When the ship starts to 15 return, and contacts 129, 130 and 132 control the circuit, the circuit through coil 201 is broken, relay 200 closes to short circuit resistance 149, so that only resistance 150 is in the circuit, and a rapid return movement of 20 the rudder is obtained.

The resistance coils 149 and 150 are manually settable to adjust the speed of the motor, and hence, of the rudder, to take care of variations in sea conditions, load of the 25 ship, etc., which may necessitate slower or more rapid operation of the rudder for equal deviations of the ship.

The motor 65 may be arranged to control 30 a steering mechanism, such as a telemotor of the usual type. Thus the motor shaft 210 may operate a pinion 211 which engages two racks 212 and 213 on opposite sides thereof. Said racks operate as plungers in cylinders 214, 215, so that rotation of pinion 211 will 35 cause one plunger to move inwardly in its cylinder and the other plunger to move outwardly. This causes a displacement of the fluid to one side which is transmitted by pipes 216, 217 connected to cylinders 214, 215 respectively, to the opposite sides of the steering engine 220, 221 which is geared to sector 222 integral with the rudder. Further details of the steering engine are not essential 40 for the purpose of disclosing the present invention, since such engines are standard commercial units and well known in the art.

It will be observed that it is the rudder 50 which controls the course control mechanism (consisting of the control device, the auxiliary control device 70 and the relays) by a follow-up mechanism. This follow-up mechanism is therefore independent of the steering engine used to operate the rudder, and 55 hence all errors arising in the telemotor, its gearing, transmission, etc. are eliminated so far as the control of the rudder positioning and limiting means are concerned. If the follow-up mechanism, which is now connected to and controlled by the rudder, were 60 connected to the steering engine, all errors arising in the latter would cause errors in the position of the rudder, and hence, in the course of the vessel. By governing the fol-

low-up mechanism from the rudder proper, 65 no such errors can arise.

It will be observed further, that the motor 65 is a series motor, one of the characteristics of which is the picking up in speed thereof the longer it runs, within a given interval. 70 Thereafter, as the counter-electromotive force builds up, the speed diminishes. This action of the motor is desirable because for small movements of the rudder only the initial comparatively slow speed of the motor is 75 utilized, but where the rudder is to be operated through greater distances, the motor picks up speed the longer it rotates and thus drives the rudder more rapidly than for small angular distances. It may occur, however, that the rudder is operated through so great an angular distance that the motor rotates long enough for the second phase, i. e., the diminishing speed, to set in. To prevent

such diminution in speed, there may be provided a relay 225, the coil 236 of which is in series with a resistance 227 in the motor circuit. When the circuit is closed, the full current passes through coil 236 so that the relay is held open against the action of spring 228 and the current passes through resistance 227. As the counter E. M. F. builds up, the current in coil 236 is decreased to a point where it can no longer overcome the tension of spring 228, and the relay is closed. 90 A short circuit is then established through the coil 236, lead 230, contacts of the relay, and lead 231 to cut out resistance 227 and so increase the current, and hence the speed of the motor. So that where the rudder is to be 95 moved through a large angular distance requiring comparatively long operation of the motor, the speed of the latter will be maintained, or even increased, throughout its operation. The system may be made sensitive 100 by employing a plurality of relays similar to 225 adapted to be operated successively to cut out an increasing amount of resistance and thus provide for acceleration of the motor 105 corresponding to the length of time during 110 which it is operated continuously.

The telemotor is, of course, responsive to changes in speed of the motor 65, so that the steering engines are in effect operated at a speed corresponding to the angular movement of the rudder, for, as pointed out above, the speed of motor 65 is increased progressively the longer it operates. 115

From the above description it is apparent that as the ship starts its yawing movement 120 to one side or the other, the rudder is moved outwardly in such a direction as to cause the ship to return, and that as soon as the ship starts to return, the rudder is moved back to initial position, allowing the momentum of 125 the ship to finish the return movement or to return slowly by repeating this cycle. The ship is thus held to its course automatically.

This device may be employed also to set the ship on a different course and maintain it thereon without the manual effort of operating the rudder. For this purpose, the handle 60 is operated to rotate ring 55 in one direction or the other, until the pointer 16 indicates on arbitrary scale 17 the change in heading. Trolley 50 being maintained in a fixed position by the repeater motor, movement of the ring 55 will bring said trolley into engagement with either contact 51 or 52. Assume that it is desired to turn the ship counterclockwise. Ring 55 is rotated clockwise through the desired angle so that trolley 50 comes into engagement with contact 51. The slight yawing movements of the ship will cause engagement between brush 71 and contact 76 to energize the motor to operate the rudder clockwise so as to turn the ship counterclockwise to bring trolley 50 to the insulating strip 54. As hereinbefore described, as soon as the ship starts to turn under influence of the rudder, the latter is brought back to initial position and thereafter the ship will turn under its own momentum. If the ship does not turn the full amount necessary to bring it on the new course, trolley 50 will remain in engagement with contact 51, but nearer the insulation 54. Upon slight yawing of the ship, brush 71 will again engage contact 76 to throw the rudder outwardly in clockwise direction. The ship again turns counterclockwise, the rudder is brought back to initial position, and the ship continues to turn under its own momentum. The operation is repeated until trolley 50 reaches insulation 54, i. e., until the ship is on its new course. Thereafter the device operates as hereinbefore described to counteract the effects of yawing and keep the vessel on its new course.

A suitable alarm or indicating device 164 having its own source of energy 165 may be connected in circuit with trolley 50 and contact strip 53, so that an alarm is sounded whenever such unusual turning or yawing of the ship takes place as will cause trolley 50 to engage said strip. This alarm may thus serve to warn against unusual atmospheric or tidal conditions or faults arising from the ship proper.

It may be found desirable to provide means permitting a rapid, continuous, uninterrupted turning of the ship when a new course is set, or when the ship departs from its course more than a few degrees, instead of the step by step movement described in the preceding description. For this purpose, means are provided whereby the rudder returning mechanism, which is ordinarily effective to return the rudder to central position as soon as the ship starts turning back from the position to which it has yawed, is rendered ineffective when a deviation from the course greater than that ordinarily due

to yawing occurs. By this construction, the rudder, instead of being returned as soon as the ship starts in the desired direction, is held outwardly to cause rapid and continuous turning of the ship, until the latter approaches the desired course, within a predetermined limit. The device embodying this principle is shown in the diagrammatic representation in Fig. 11 in which parts which are the same as in Fig. 10 are similarly numbered.

A trolley 50' is in the form of a lever which carries three contacts 168, 169 and 170, the first two upon one arm thereof and the last upon the other arm. Contacts 168 and 170 engage strips 51, 52, 171, 172, 173 and 174 of a contact ring 55', similar to 55, while contact 169 engages a separate contact 176.

The operation of the device is as follows; *Case 1.*—Assume slight yawing movement in a clockwise direction insufficient to move contact 168 off insulation 54. A circuit is then established through main lead 140, contact 169, contact 176, lead 141, contact 132, brush 129, relays 134 and 82 to energize relay 84 and coil 63 of the motor to drive the rudder in clockwise direction and move the ship counterclockwise to counteract the yaw. The end of the rudder 66 is provided with or connected to a block 178 which closes a set of contacts 179, when said rudder moves as described, to close a circuit from main lead 140, lead 180, contacts 179, to energize coil 156 of relay 134 to break the circuit through coil 63 of the motor. The rudder is held in this position until the ship turns back counterclockwise sufficiently to cause brush 130 to be moved into engagement with contact 132 to establish a circuit through main lead 140, contact 169, contact 176, lead 141, contact 132, brush 130, relays 143 and 90 to energize relay 92 and coil 62 of the motor to drive the rudder in the opposite direction, i. e., counterclockwise to turn the ship clockwise.

When the rudder engages and closes contacts 181, coil 147 is energized to break the circuit through coil 62 of the motor. The rudder is held in this position until the ship turns back clockwise sufficiently to bring brush 129 into engagement with contact 132. These small oscillations of the rudder between contacts 179 and 181 are thus continued during the small yawing movements of the ship to counteract said movements.

Case 2.—Assume greater deviations of the ship so that contact 168 engages contact 51 or 52, that contact 170 does not move out of engagement with contact 174, and that contact 169 does not move out of engagement with contact 176. If the ship yaws clockwise, the circuit is as follows: Main lead 140, contacts 168 and 51', lead 79, contact 76, brush 71, lead 80, relays 82 and 84 to energize coil 63 of the motor to drive the rudder clockwise and thus turn the ship back counterclockwise

to counteract the yaw. For a short distance beyond the insulation 54 a circuit will also be established through main lead 140, contacts 169 and 176, lead 141, contact 132, brush 129, 5 relays 134, 82 and 84, to coil 63. When the rudder reaches contacts 183, it closes them to establish a circuit through main lead 140, contacts 170 and 174, lead 184, contacts 183 to energize coil 81 of relay 82 and break the 10 circuit through coil 63 of the motor. As soon as the ship starts to turn counterclockwise, brush 71 moves off contact 76 while contact 168 is still on contact 51, this operation being similar to that in Fig. 10 and the mechanism 15 for effecting it being the same i. e., the slip-friction connection of Fig. 9, which limits the movement of the commutator 75 relative to the brushes 71 and 72. Brush 72 engages contact 77 but no circuit is established. 20 Brush 130 engages contact 132 to establish a circuit from main lead 140, contacts 169 and 176, lead 141, contact 132, brush 130, relays 143, 90 and 92 to energize coil 62 of the motor and drive the rudder counterclockwise. 25 The ship continues its counterclockwise movement back to its course under its own momentum. When the rudder reaches contacts 181, at or slightly beyond its central position in order to effect rapid stopping of the ship's 30 turning, it closes them to energize coil 147 and break the circuit through coil 62 of the motor.

If the ship yaws in a counterclockwise direction, the lower set of relays energizes coil 35 62 of the motor to drive the rudder counterclockwise and so turn the ship clockwise back to its course. When the rudder reaches contact 187 a circuit is closed through main lead 140, contacts 170 and 174, leads 184 and 186, 40 contacts 187, lead 188 to energize coil 89 of relay 90 to break the circuit through coil 62. As soon as the ship starts to turn back clockwise, brush 129 establishes a circuit through the upper set of relays to energize coil 63 of the motor to drive the rudder clockwise. 45 The ship continues to turn clockwise under its own momentum which carries it back to its course. When the rudder reaches the centralizing contacts 179, beyond its central position to assist in stopping the ship's turning, the coil 156 is energized to break the circuit through coil 63 of the motor.

In Case 2, the device of Fig. 11 operates in part similarly to the device in Fig. 10, i. e., 55 the rudder is thrown outwardly upon yaw of the ship, in such direction as to move the ship back to its course, and as soon as the ship starts back, the rudder is returned, leaving the ship to swing back upon its course 60 under its own momentum. In addition, the rudder may be returned slightly beyond its central position to effect rapid stopping of the ship's turning movement.

Case 3.—Assume in Case 2 that the deviations are sufficient to move contact 170 into

engagement with contacts 172 and 173. The same circuits would be established as in Case 2 and the operation is the same, except that the limiting positions of the rudder would be at a greater angular distance to correspond 70 to the greater deviation of the ship. The rudder would engage contacts 189 or 190 instead of 183 or 187. When the rudder moves clockwise, a circuit is established from main lead 140, through contacts 170 and 173, lead 75 198, contacts 189, through coil 81 to break the circuit through field coil 63 of the motor. When the rudder moves counterclockwise, the circuit is from main lead 140, contacts 170 and 172, lead 198, lead 191, contacts 190, 80 through coil 89 of relay 90 to break the circuit through coil 62.

Case 4.—Assume that ring 55' is turned to set a new course, or that for some reason, the ship is turned more than 10° (say) off 85 its course, such that contact 169 moves beyond contact 176 and contact 170 moves beyond contacts 172 and 173, but that contact 168 still engages contacts 51 or 52. It may be assumed that a new course is set because 90 of the improbability of yaw to this extent taking place. However, whether this deviation is due to yaw or to setting a new course, the operation will be the same. Assume that counterclockwise movement of the ship is 95 necessary to bring it to its new course. A circuit is established through contact 51, brush 71, relays 82 and 84 to coil 63 of the motor. The rudder moves clockwise to cause the ship to move counterclockwise as desired, 100 and when said rudder reaches its limiting position, it closes contacts 193 to energize coil 81 of the relay 82 which breaks the circuit through coil 63. As the ship starts to turn in the desired direction, however, no circuit 105 is established through the other coil of the motor to reverse the direction of the rudder, as in Fig. 10 and in Cases 1, 2 and 3, since contact 169 is off contact 176 and there is no circuit through brush 130 to the other coil 110 of the motor, even though said brush is on contact 138 due to the counterclockwise turning of the ship. The rudder therefore holds its extreme position, causing the ship to be turned rapidly and continuously, until as the 115 ship nears its course, contact 169 engages contact 176 to establish a circuit through contact 132, brush 130, relays 143 and 92 to field coil 62 of the motor 65 to return the rudder to a point slightly beyond its central position as in the previous cases, to effect a rapid stopping of the ship's turning. From this point the momentum of the ship is sufficient to carry it substantially to its course, which it approaches slowly as heretofore described, 120 when contact 50 will engage insulation 54.

The circuits when the ship is to be turned clockwise, will be readily apparent, and will lie through contact 52, brush 72 and the lower set of relays to coil 62 of the motor to move 125 130

the rudder counterclockwise and move the ship clockwise. In its extreme position the rudder causes contacts 194 to engage and energize coil 89 of relay 90 to break the circuit through coil 62. The rudder is held in extreme position until the ship turns so that contact 169 engages contact 176 to establish a circuit through contact 132, brush 129, relays 134, 82 and 84 to coil 63 of the motor. The rudder is operated clockwise and is returned to centralized position where it is held by closing contacts 179 to energize coil 156 of relay 134 to break the circuit through coil 63 of the motor.

It is thus apparent that when the ship is to be moved through large angular distances either to return it to its course after an exceptionally large yawing movement, or when a new course is set involving a large deviation from the previous course, the rudder is thrown outwardly and held in its extreme position until the vessel has moved through the greater part of the required angular distance in the desired direction. As the vessel nears its course, the rudder is swung back to substantially centralized position and the angular movement of the ship damped out by the time it reaches its course. By this means a rapid change of course may be accomplished for large angular distances instead of the retarded movement disclosed in Fig. 10.

It will also be apparent from the description of the device in Fig. 11 that a plurality of intermediate limiting positions for the rudder are provided by the contacts 183, 187, 189 and 190, in addition to the centralized and extreme limit positions of Fig. 10. The plurality of limiting positions correspond to the varying degrees of yaw or varying degrees of change in course, so that the throw of the rudder is in proportion to the amount of deviation. Thus, for a change in course insufficient to cause contact 170 to leave contact 174, the rudder will move until it closes contacts 183 or 187; for a change in course sufficient to cause contact 170 to engage contacts 172 or 173, the rudder will move until it engages contacts 189 or 190.

Between motor 65 and the rudder, there may be interposed a similar type of steering telemotor as in the device of Fig. 10. Here, also, the follow-up mechanism for controlling the circuit in accordance with the positions of the rudder, is connected to and leads from the rudder proper. No errors existing in the transmission system of the telemotor can possibly be transmitted to the rudder to give an incorrect position to the latter, as would be the case if the follow-up mechanism were operated by the steering engine rather than directly from the rudder.

Similar to the Fig. 10 device there may be interposed in the motor circuit, one or a plurality of relays 225 to cause the motor to accelerate the greater the angular distance

through which the rudder is operated, and the longer the period of operation of the motor. Thus, as the rudder is moved to engage only contacts 179, the initial speed of the motor is sufficient, but where the rudder is driven to engage contacts 193, it may be found that the motor has diminished in speed before the rudder has reached its limiting position. By the use of these relays, as described in connection with Fig. 10, more resistance is cut out of the circuit the longer the motor rotates, and thus increases or sustains the speed of the motor.

It will be further apparent that in both the modifications of Figs. 10 and 11, it is immaterial how trolley 50 comes into engagement with contact 51 or 52 (or 51', 52'), whether through yawing of the ship, or because the ring 55 or 55' is displaced by handle 60 to set a new course. In either case, the operation is the same, i. e., the ship is so turned automatically as to move insulating strip 54 into engagement with trolley 50.

The device shown in Fig. 11 may be provided with the alarm 164, as in Fig. 10, in circuit with trolley 50' and contacts 171 through leads 195 and 140, said alarm functioning as described in connection with the device in Fig. 10.

If a record is kept of the movements of a rudder operated by my automatic steering mechanism, it will appear as in Fig. 12 which is a portion of an actual record. The course or amidships position of the rudder is indicated by the line in the left hand graph. It will be observed that most of the deviations are between the lines Y, corresponding to the distance between contacts 179 and 181. Occasionally, there is a deviation to lines Z, corresponding to contacts 183 and 187. Ordinary yawing movements exceed these angular distances. However, yaw may take place between contacts 189 and 190, which would be indicated by lines W, or between contacts 193 and 194 indicated by lines V. These records will, of course, be made also when the rudder is thrown outwardly for a change of course.

The right hand graph in Fig. 12, indicates the course of the ship, and it is evident that the movements of the rudder are in exactly opposite direction and indicates an almost instantaneous response of the rudder to changes in the ship's course. The graph of the rudder movements is full scale, but the graph of the ship's deviations is magnified considerably, so that actually the deviations of the ship from its course are inappreciable.

In accordance with the provisions of the patent statutes, I have herein described the principle of operation of my invention, together with the apparatus, which I now consider to represent the best embodiment thereof, but I desire to have it understood that the apparatus shown is only illustrative and that

the invention can be carried out by other means. Also, while it is designed to use the various features and elements in the combination and relations described, some of these 5 may be altered and others omitted without interfering with the more general results outlined, and the invention extends to such use.

Having herein described my invention, 10 what I claim and desire to secure by Letters Patent is,

1. In an automatic steering mechanism, means responsive to the movement of a vessel off its course for opposing said movement 15 and tending to return the vessel to its course, and means for rendering said first named means ineffective when said vessel starts on its return movement.

2. In an automatic steering mechanism, 20 means responsive to the movement of a vessel off its course for opposing said movement and operating to return the vessel to its course, and means actuated on the initial return movement of said vessel for rendering 25 said first named means ineffective before said vessel reaches its course.

3. In an automatic steering mechanism, 30 means responsive to the movement of a vessel off its course for counteracting said movement and imparting a return momentum to said vessel, and means for rendering said first named means ineffective before said vessel reaches its course.

4. In an automatic steering mechanism, 35 a controller responsive to the deviation of a vessel off its course for counteracting said movement and returning said vessel to its course, a second controller responsive to change in the direction of yaw, a steering engine, and means including interlocking relays between said controllers and engine whereby the tendency of the vessel to overrun its course when being returned to its course after deviation is counteracted.

45 5. In an automatic steering mechanism for a vessel having a rudder, a controller responsive to the movement of the vessel off its course for operating the rudder in a direction to counteract said movement and return the vessel to its course, said rudder being normally positioned to maintain the vessel on its course, a second controller responsive to change in the direction of yaw of the ship, a steering engine, and interlocking relays between said controllers and engine whereby the rudder is returned to its normal position before the vessel swings back to its original course.

60 6. In an automatic steering mechanism for dirigible craft, means for setting a new course for the craft, means rendered effective by said first named means for operating said craft toward the new course, and means whereby said last named means is rendered

ineffective before said craft reaches said new 65 course.

7. In an automatic steering mechanism for dirigible craft, means for setting a new course for the craft, and means rendered effective by said first named means for imparting a plurality of successively diminishing impulses to said craft for bringing it toward the new course.

8. In an automatic steering mechanism for dirigible craft, said craft having a rudder normally in centralized position when said craft is traveling on its course, means responsive to the movement of the craft off its course for operating the rudder in a direction to counteract said movement and return the craft to its course, means for returning said rudder before the craft reaches its course, and means whereby said last named means is rendered ineffective when the rudder reaches its substantially centralized position.

9. In an automatic steering mechanism for dirigible craft, said craft having a rudder normally in centralized position when said craft is traveling on its course, means responsive to the movement of the craft off its course for operating the rudder in a direction to counteract said movement and return the craft to its course, means for returning said rudder before the craft reaches its course, and means operated by said rudder when the latter reaches its substantially centralized position for rendering said last named means ineffective.

10. In an automatic steering mechanism, 100 means responsive to the movement of a vessel off its course for counteracting said movement, said means comprising means for imparting a plurality of successively diminishing impulses to said vessel, all of said impulses being in the same direction for restoring it to its course.

11. In an automatic steering mechanism, 110 means responsive to the movement of a vessel off its course for counteracting said movement, said means comprising means for imparting a plurality of successively diminishing impulses to said vessel, all of said impulses being in the same direction for restoring it to its course and means whereby said last named means is rendered ineffective when said vessel reaches its course.

12. In an automatic steering mechanism for dirigible craft, means for setting a new course for the craft, means rendered effective by said first named means for imparting a plurality of successively diminishing impulses to said craft for bringing it toward the new course and means whereby said last named means is rendered ineffective when said craft reaches the new course.

13. In an automatic steering mechanism for dirigible craft having a rudder, a course

control device responsive to turning of the craft, a reversible engine for controlling the rudder of the craft, an auxiliary control device responsive to changes in the direction of turning of the craft, means interconnecting said devices and engine whereby the position of said rudder depends on both the heading and the angular movement of the ship at the time, said engine being inoperative when said craft is on its course, means whereby said devices operate when said craft moves off its course, to drive said engine and operate the rudder in a direction for returning the craft to its course, means whereby said auxiliary device responds to the return movement of the craft to reverse the direction of operation of said engine before the craft reaches its course, and means operated by said rudder in substantially centralized position for rendering said last named means ineffective.

14. In an automatic steering mechanism for dirigible craft having a rudder, a course control device responsive to turning of the craft, a reversible engine for controlling the rudder of the craft, an auxiliary control device responsive to changes in the direction of turning of the craft, means interconnecting said devices and engine whereby the position of said rudder depends on both the heading and the angular movement of the ship at the time, said engine being inoperative when said craft is on its course, means whereby said devices operate when said craft moves off its course to drive said engine and operate the rudder in a direction for returning the craft to its course and means operated by said rudder in its limiting positions to render said last named means ineffective.

15. In an automatic steering mechanism for dirigible craft having a rudder, a course control device responsive to turning of the craft, a reversible engine for controlling the rudder of the craft, an auxiliary control device responsive to changes in the direction of turning of the craft, means interconnecting said devices and engine whereby the position of said rudder depends on both the heading and the angular movement of the ship at the time, said engine being inoperative when said craft is on its course, means whereby said devices operate when said craft moves off its course, to drive said engine and operate the rudder in a direction for returning the craft to its course, means operated by said rudder in its limiting positions to render said last named means ineffective, means whereby said auxiliary device responds to the return movement of the craft to reverse the direction of operation of said engine before the craft reaches its course, and means operated by said rudder in substantially centralized position for rendering said last named means ineffective.

16. In an automatic steering mechanism

for dirigible craft having a rudder, a course control device responsive to turning of the craft, a reversible engine for controlling the rudder of the craft, an auxiliary control device responsive to changes in the direction of turning of the craft, means interconnecting said devices and engine whereby the position of said rudder depends on both the heading and the angular movement of the ship at the time, said engine being inoperative when said craft is on its course, means whereby said devices operate when said craft moves off its course, to drive said engine and operate the rudder in a direction for returning the craft to its course, means whereby said auxiliary device responds to the return movement of the craft to reverse the direction of operation of said engine before the craft reaches its course, means operated by said rudder in substantially centralized position for rendering said last named means ineffective and means whereby said devices operate said engine a plurality of times in a direction to return the craft to its course.

17. In an automatic steering mechanism for dirigible craft having a rudder, a course control device responsive to turning of the craft, a reversible engine for controlling the rudder of the craft, an auxiliary control device responsive to changes in the direction of turning of the craft, means interconnecting said devices and engines whereby the position of said rudder depends on both the heading and the angular movement of the ship at the time, said course-control device being operable to set a new course, means whereby said devices operate to drive said engines to operate the rudder in a direction for moving the craft to its new course, means whereby said auxiliary device operates to restore said rudder to initial position when said craft moves toward the desired course and means whereby said devices operate said rudder repeatedly to drive the craft in the desired direction until the craft reaches its new course.

18. In an automatic steering mechanism for dirigible craft, a course control device responsive to the movements of a gyro compass, a reversible motor for controlling the rudder of the craft, an auxiliary device also responsive to the movements of said compass and interposed between said control device and the motor, said motor being inoperative when said craft is on its course, means whereby said devices operate when said craft moves off its course, to drive said motor and operate the rudder in a direction for returning the craft to its course, and a slip-friction connection interposed between said auxiliary device and said compass for limiting the movements of said auxiliary device, so that said auxiliary device reverses the direction of rotation of said motor before the craft reaches its course.

19. In an automatic steering mechanism

for dirigible craft, means responsive to the movements of the craft off its course for displacing the rudder for counteracting said movement and returning the craft to its course, means for returning the rudder toward the central position for retarding angular return movement of the craft, and means whereby said last named means is rendered inoperative for a portion of the return movement of the craft when the craft is being returned through a relatively large angular distance.

20. In an automatic steering mechanism for dirigible craft, means responsive to the movements of the craft off its course for counteracting said movement and returning the craft to its course, means for retarding angular return movement of the craft, and means whereby said last named means is rendered inoperative for a portion of the return movement of the craft when the craft is to be returned through a relatively large angular distance and again rendered operative as the craft approaches its course.

25. 21. In an automatic steering mechanism for dirigible craft, means for setting a new course for the craft, means rendered effective by said first-named means for operating said craft toward the new course, means for retarding angular movement of the craft toward said new course, and means whereby said last named means is rendered inoperative for a portion of the return movement of the craft when said craft is being returned through a relatively large angular distance.

22. In an automatic steering mechanism for dirigible craft, means for setting a new course for the craft, means rendered effective by said first-named means for operating said craft toward the new course, means for retarding angular movement of the craft toward said new course, and means whereby said last named means is rendered inoperative for a portion of the return movement of the craft when said craft is to be turned through a relatively large angular distance and is again rendered operative as the craft approaches the new course.

23. In an automatic steering mechanism for dirigible craft having a rudder, a master controller responsive to the movements of the craft off its course for operating said rudder in a direction for counteracting said movements and returning the vessel to its course, and means independent of said controller and operated by said rudder for stopping said rudder when said rudder is operated through an angular distance proportional to the movements of the craft off its course.

24. In an automatic steering mechanism for dirigible craft having a rudder, means for setting a new course for the craft, means actuated by said first named means for oper-

ating the rudder in a direction to move the craft to its new course, means whereby said rudder is moved through an angular distance proportional to the angular distance through which the craft is to be turned, and means for returning the rudder, when the craft approaches its new course, to a point slightly beyond its central position.

25. In an automatic steering mechanism adapted to be controlled by a gyro compass subject to "hunting," a master controller operatively connected to said compass, and means for preventing transmission of the "hunt" of said compass to said controller, said means comprising a two-part connection between said compass and said controller, one of said parts having an operating member, and the other of said parts having a tapered slot in which said operating member operates loosely to effect lost-motion, and means for adjusting the position of said operating member in said slot to vary the amount of lost-motion.

26. In an automatic steering mechanism adapted to be controlled by a gyro compass subject to "hunting," a master controller operatively connected to said compass, and means for preventing transmission of the "hunt" of said compass to said controller, said means comprising an operating member operated by said compass, said member having a tapered slot in which said operating member operates loosely to effect lost-motion, and means for adjusting the position of said operating member in said slot to vary the amount of lost-motion.

27. In an automatic steering mechanism adapted to be controlled by a gyro-compass, a casing, a repeater motor in said casing and operated by said compass, a member in said casing and operated by said motor, and means for preventing transmission of the "hunt" of said motor to said member, said means comprising an operating member operated by said motor, said member having a vertically positioned wedge-shaped opening in which said operating member operates loosely to effect lost motion, and means positioned outside of said casing whereby the position of said operating member in said opening may be adjusted to vary the amount of lost motion.

28. In an automatic steering mechanism adapted to be controlled by a gyro compass, a casing, a repeater motor in said casing and operated by said compass, a member in said casing and operated by said motor, and means for preventing transmission of the "hunt" of said motor to said member, said means comprising an operating member operated by said motor, said member having a vertically-positioned wedge-shaped opening in which said operating member operates loosely to effect lost-motion, a cam member engaging said operating member, and means positioned

outside of said casing for operating said cam member to adjust the position of said operating member in said opening to vary the amount of lost motion.

5 29. In an automatic steering mechanism for dirigible craft having a rudder, a course control device responsive to turning of the craft, an auxiliary control device responsive to turning of the craft, a reversible engine 10 for controlling the rudder, means controlled by said rudder, and interlocking relays for controlling said engine, said devices and said rudder controlled means controlling said relays.

15 30. In an automatic steering mechanism for dirigible craft having a rudder, a reversible steering engine for controlling the rudder, a plurality of relays for controlling said engine, means responsive to the turning of 20 the craft off its course for actuating certain of said relays to operate the engine and drive the rudder in a direction to bring the craft back to its course, and means responsive to a change in the direction of turning of the craft 25 for actuating certain of said relays to operate the engine and drive the rudder in a reverse direction.

31. In an automatic steering mechanism for dirigible craft having a rudder, a reversible motor for controlling the rudder, a plurality of relays for controlling said motor, means responsive to the turning of the craft off its course for actuating one of said sets of relays to operate the motor and drive the 35 rudder in a direction to bring the craft back on its course, means actuated by the rudder for rendering said last named set of relays ineffective, and means responsive to a change in the direction of turning of the craft for 40 actuating a second set of relays to operate the motor and drive the rudder in a reverse direction.

32. In an automatic steering mechanism for dirigible craft having a rudder, a reversible motor for controlling the rudder, a plurality of relays for controlling said motor, means responsive to the turning of the craft off its course for actuating one of said 45 relays to operate the motor and drive the rudder in a direction to bring the craft back on its course, means actuated by the rudder for rendering said last named relay ineffective, means responsive to the direction of turning of the craft for actuating a second relay to 50 operate the motor and drive the rudder in a reverse direction, and means actuated by the rudder for rendering the second relay ineffective.

33. In an automatic steering mechanism 55 for dirigible craft having a rudder, means responsive to the movement of the craft off its course for operating the rudder in a direction to counteract said movement and re-

turn the craft to its course and means for returning the rudder to initial position at a greater speed than said rudder was operated outwardly.

34. In an automatic steering mechanism for dirigible craft having a rudder, means responsive to the movement of the craft off 70 its course for operating the rudder in a direction to counteract said movement and return the craft to its course and means actuated on the return movement of the craft for returning the rudder to initial position 75 at a greater speed than said rudder was operated outwardly.

35. In an automatic steering mechanism for dirigible craft having a rudder, means responsive to the movement of the craft off 80 its course for operating the rudder in a direction to counteract said movement and return the craft to its course, means for returning the rudder to initial position, and means whereby the outward movement of the 85 rudder and the return movement thereof are performed at different speeds.

36. In an automatic steering mechanism for dirigible craft having a rudder, means responsive to the movement of the craft off its 90 course for operating the rudder in a direction to counteract said movement and return the craft to its course, means for returning the rudder to initial position, and means whereby the rudder is moved outwardly at a speed 95 relatively slow compared with the speed of the return movement thereof.

37. In an automatic steering mechanism for dirigible craft having a rudder, an electrical course controller, means actuated by 100 said controller for turning said rudder, said means including an electric motor adjacent said controller and actuated thereby, a telemotor system actuated by said motor, a steering engine controlled by the telemotor for 105 turning the rudder, and a second electrical controller actuated by the movements of the rudder providing a follow-back system independent of said telemotor.

38. In an automatic steering mechanism 110 for a vessel having a rudder, a controller responsive to the movement of the vessel off its course for operating the rudder in a direction to counteract said movement and return the vessel to its course, said rudder being normally positioned to maintain the vessel on its course, a second controller responsive to change in the direction of yaw of the ship, a steering engine, and means actuated by said 115 second controller alone whereby the rudder is returned to normal position before the vessel swings back to its original course.

In testimony whereof I have affixed my signature.

CHESTER B. MILLS.
